UNITED STATES PATENT OFFICE.

OSCAR E. NICKEY, OF BIGSPRING, TEXAS.

LOCK.

SPECIFICATION forming part of Letters Patent No. 710,505, dated October 7, 1902.

Application filed February 19, 1902. Serial No. 94,799. (No model.)

To all whom it may concern:

Be it known that I, OSCAR E. NICKEY, a citizen of the United States, residing at Bigspring, in the county of Howard and State of Texas, 5 have invented a new and useful Lock, of which the following is a specification.

The present invention is a permutation lock, and while relating particularly to padlocks it will be seen by those skilled in this 10 art that certain features may be employed in connection with locks of a different character.

One of the objects of this invention is to provide simple permutation mechanism in which the combination may be readily changed and 15 varied a great number of times without the necessity of disassociating the members or elements, the combination-changing devices, however, being positively secured against accidental displacement, thereby obviating any 20 danger of unintended changes of combination while locked.

Other features relate to improvements in certain details of construction whereby a lock is formed that is an exceedingly simple and 25 therefore inexpensive structure, readily operable by one acquainted with the combination, but not capable of being understood or "picked" by one ignorant of said combination.

30 The preferred embodiment of the invention is fully illustrated in the accompanying drawings, and the construction set forth therein is described in the following specification; but, as already stated, the invention is not 35 to be limited to use in padlocks, as shown, nor to the specific structure set forth, as certain changes may be made therefrom, provided such changes are within the scope of the claims hereto appended.

40 In the drawings, Figure 1 is a side elevation of a padlock embodying the present invention. Fig. 2 is a similar view with the cover removed, showing the interior arrangement of the mechanism. Fig. 3 is a reverse view 45 to that shown in Fig. 2, the back of the casing being removed. Fig. 4 is a longitudinal sectional view through the lock. Fig. 5 is a transverse sectional view. Fig. 6 is a view 50 similar to Fig. 2, with the exception that the outer tumbler and the actuating-arm are removed. Fig. 7 is a perspective view of the several tumblers employed, said tumblers be-

ing separated, but shown in proper order. Fig. 8 is a detail perspective view of the tooth-carrying arm for the rear tumbler. Fig. 9 is 55 a perspective view of the tumbler-actuating arm. Fig. 10 is a detail perspective view of the shackle-latch and link. Fig. 11 is a face view of one of the spacing-washers.

Similar numerals of reference designate corresponding parts in all the figures of the drawings.

The casing is in the form of the usual-shaped boxing, comprising a rear face-plate 10, having an integral rim 11, that extends 65 about three sides of the same, a cover 12 covering the opposite face and being secured in place by tie-pins 13, which are riveted to the opposite plates, as will be readily understood. This cover is provided with suitable lugs 14, 70 which fit within the rim, and thus position said cover while being fastened in place. Pivoted within one corner of the casing is the shackle 15, having suitable journals or gudgeons 16, which are seated in suitable sockets 75 made for the purpose in the facing-plates. The opposite or free end of the shackle is reduced in thickness and has a terminal hook 17, which engages in the casing when said shackle is closed. It is arranged, however, to be 80 thrown to open position by means of a spring 18, coiled about one of the tie-pins 13 and having an arm 19, which bears against a preferably curved projection 20, that is located upon the pivoted end of the shackle. 85 This spring is preferably formed of a single piece of wire coiled to proper shape and pressing against the projection, so as to cause the shackle to fly open when unlocked. The opening in the casing between the two terminals of the shackle is closed by a cap-plate 90 21, hinged upon one of the tie-pins 13 and having a depending catch 22, that detachably engages about another of said tie-pins. This cap-plate is locked in its closed position 95 by lugs 23, located upon the shackle and projecting over the ends of the cap-plate when said shackle is in closed position. As a result the cap-plate will be securely locked when the shackle is locked. The terminals 100 11^a of the rim are bent inwardly to meet the ends of the cap-plate 21, said terminals being bifurcated to embrace the ends of the shackles. Pivoted upon still another of the tie-

pins is a holding-latch 24, having a hook portion 25 at its upper end that engages the hook 17 of the shackle to hold said shackle in closed position. This latch is urged into its locking engagement by means of a spring 26, bearing at one end against the casing and at the other end against the movable hook portion, having an intermediate part coiled about the tie-pin. The forward movement of said latch is furthermore limited by a stoppin 27, located in front of the same and directly beneath the hook 17 of the shackle. The means for operating the latch 24 is preferably constructed as follows: Upon the inner face of the rear plate 10 is a boss 28, having an angular socket 29, in which is fitted the angular end of a tumbler-post 30, and on said post is rotatably mounted a plurality of tumblers, (designated, respectively, 31, 32, 33, and 34.) The several tumblers, as clearly shown in Fig. 7, are in the form of flat disks, each having a notch 36 in its edge. The rear tumbler 31 is provided with a circular series of sockets or openings 37 and an intermediate arcuate slot 38. A tooth-carrier 39 (clearly illustrated in Fig. 8) is journaled upon the post 30 beneath the tumbler 31 and is adjustably and detachably connected therewith. To this end said carrier is in the form of an arm having a tooth 40 at one end which projects through the arcuate opening 38, as clearly shown in Fig. 5. The other end of this arm carries a movably-mounted stud 41, secured to a flat leaf-spring 42, which really constitutes a part of the arm, said spring being held against lateral movement by a guide-block 43, movably mounted in a socket 44 in the arm. The stud 41 detachably engages in the sockets or openings 37 of the rear tumbler 31, and as a result said arm and the tooth 40, carried by it, will be moved simultaneously with the tumbler; but by disengaging the stud 41 and moving the arm about the relation of the tooth 40 with the notch 36 may be changed. The two intermediate tumblers 32 and 33 are provided on their opposite faces with coacting teeth 45, one of the teeth of the tumbler 32 being arranged to engage with the tooth 40 of the rear tumbler. For the sake of cheapness these teeth are preferably made integral with the tumblers by being cut or struck up from the said tumblers, as clearly shown in the drawings. The front tumbler 34 is also provided with a circular series of sockets or openings 46, and one face of its peripheral notch is beveled, as shown at 47. This tumbler is provided with teeth upon its rear face only, which teeth coact with the teeth of the adjacent tumbler 33, as will be readily understood. This front tumbler is actuated through the medium of an operating-stem 48, that projects through the cover of the casing and carries an actuating-arm 49, rigidly secured thereto, and having a spring-pressed stud 50, which detachably engages in the sockets 46. The arrangement of this stud is clearly illustrated in Fig. 9, being

secured to a flat spring 51, which spring is held against independent lateral movement by a guide-block 52, movably mounted in a suitable socket 53 in the end of the arm. The inner end of the operating-stem is provided with a central conical seat 54, in which the front end of the tumbler-post is situated, and said tumbler-post is thereby securely held against displacement. The outer or exposed end of the operating-stem has a suitably-milled head 55 and an indicating-dial 56, provided with a suitable scale. (Shown in Fig. 1.) This dial is surrounded by a raised rim 57, having a transverse indicating-notch 58.

The several tumblers are spaced apart by washers 59, said washers having notches 60 at their opposite ends, in which a pair of the tie-pins 13 engage, said tie-pins being located on opposite sides of the tumbler-post and securely holding the washers in place. Said washers are provided with enlarged central openings 61, through which the tumbler-post passes and in which are located the coacting teeth of the adjacent tumblers. The washers thereby hold the tumblers spaced apart, so that there will be no frictional contact between them, and at the same time permit the proper coaction of the teeth.

Pivoted to the free end of the latch 24 is a link 62, having at its free end a depending hook 63, which rides upon the peripheries of the tumblers and seats itself in the notches thereof when said notches are alined beneath it. In order to properly hold the hook 63 in coacting engagement with the tumblers, the link is provided with a spring 64, preferably made integral therewith, as shown in Fig. 10, and bearing against the under side of the cap-plate 21.

The operation of the mechanism may probably be best described as follows: Assuming the shackle open and the notches of the several tumblers in alinement, with the hook 63 of the link seated therein, it will be evident that when said shackle is closed its hook will interlock with the hook of the latch 24, and as long as the notches remain in alinement by simply turning the operating-head to the right the foremost tumbler will be correspondingly rotated and the sharp shoulder or hook of the notch engaging with the hook 63 of the link will withdraw the latch from its interlocking engagement and the shackle will fly open. On the other hand, upon turning the head to the left the hook 63 will ride up on the periphery of the outer tumbler 34, and the teeth of said tumbler coming into engagement with the next tumbler will actuate the same, and thereby throw its notch out of alinement. The head can thereupon be rotated in either direction indefinitely without bringing the notches into alinement. To open the lock, however, a person knowing the combination will turn the head in one direction until the notch of the rearmost tumbler is in alinement with the hook 63, this position being indicated by a suitable number upon the dial-plate alining

with the notch 58 of the rim. The movement of the head is thereupon reversed until the predetermined number of the dial-plate alining with the notch 58 indicates that the notch 5 of the second tumbler alines with the hook 63 of the link. By thus rotating the head back and forth the operator alines the three rear-most notches with the hook of the link, and upon the last rotation when the notch of the 10 foremost tumbler alines with those of the others said hook will drop into the same and the latch will be withdrawn, as above described. The manner of changing the combination is very simple. The shackle is first 15 opened and the cap-plate 21 thrown back. This will expose the interior mechanism, so that by inserting the blade of a knife or other instrument either of the studs 41 or 50 of the arms 39 and 49 may be disengaged from 20 their respective sockets and said arms rotate and engage in other sockets. This will throw the tooth 40 of the rear tumbler into a different relation with respect to the notch 36 of the same, and in like manner will change the 25 relation of the indicator-disk 56 and the notch 36 of the front tumbler. The combination is then worked out, which can be readily done by operating the head 55 and noticing the proper numbers upon the indicating-dial 30 when the several notches are brought into alinement, the cap-plate being still open. In this manner the combination may be completely changed, so that entirely different sets of figures can be employed and the sequence 35 completely altered.

The advantages for this structure may be summed up as follows: In the first place it will be seen that the structure as a whole is made up of simple elements which will not 40 easily become deranged and will withstand rough usage, at the same time being very inexpensive. Further than this, the combination may be readily changed without dismembering the lock, the combination-changing 45 devices, however, being positively locked against accidental displacement, so that there is no danger of the combination becoming accidentally changed while the lock is in closed position.

50 From the foregoing it is thought that the construction, operation, and many advantages of the herein-described invention will be apparent to those skilled in the art without further description, and it will be understood that various changes in the size, shape, proportion, and minor details of construction may be resorted to without departing from the spirit or sacrificing any of the advantages of the invention. For instance, the 55 invention is not to be limited solely to padlocks, and different numbers of tumblers may be employed. It will also be understood that the tooth upon the rearmost tumbler may be made integral therewith in certain cases where 60 a simple lock is desired, although I consider this a very important feature of the inven-

tion, as it multiplies the number of different combinations that may be made.

Having thus described my invention, what I claim as new, and desire to secure by Letters 70 Patent, is—

1. In a lock, the combination with an operating-stem, of a rotatable tumbler, an arm secured to and movable with the stem, a separate spring resting against the arm, and a 75 holding-stud carried by the spring and having a detachable and adjustable engagement with the tumbler.

2. In a lock, the combination with an operating-stem, of a rotatable tumbler, an arm 80 secured to and movable with the stem, said arm having a guideway, a holding-stud slidably mounted in the guideway and having a detachable engagement with the tumbler, and a spring for urging the stud into such en- 85 gagement.

3. In a lock, the combination with an operating-stem, of a rotatable tumbler, an arm secured to and movable with the stem, said arm having a guideway in its free end, a flat 90 metal spring secured to the stem and resting upon the arm, and a holding-stud secured to the free end of the spring, said stud passing through the guideway and having a detachable engagement with the tumbler. 95

4. In a permutation-lock, the combination with a rotary tumbler, of combination-changing devices including an arm having a guideway, a holding-stud slidably mounted in the guideway and detachably engaging the tumbler, and a spring engaging the stud to urge the same into its said engagement. 100

5. In a lock, the combination with coacting rotatable tumblers, one of which is provided with a tooth, of an arm movable independently of both tumblers, said arm carrying a tooth that coacts with the tooth of the said tumbler, and a holding-stud also carried by the arm and detachably engaging the other tumbler. 105

6. In a lock, the combination with coacting rotatable tumblers, one of which is provided with a tooth, of an arm movable independently of both tumblers, said arm carrying a tooth that coacts with the tooth of said tumbler, and a holding-stud yieldingly mounted upon the arm and detachably engaging the other tumbler. 110

7. In a lock, the combination with a tumbler-post, of coacting tumblers journaled upon the post, one of said tumblers being provided with a tooth, the other having a plurality of sockets, of an arm also journaled upon the post and movable independently of the tumblers, said arm carrying a tooth that coacts 115 with the tooth of said tumbler, and a holding-stud that detachably and adjustably engages in the sockets of the other tumbler. 120

8. In a lock, the combination with coacting rotatable tumblers one of which is provided 130 with a tooth, of an independently-rotatable arm carrying a movable holding-stud that de-

tachably engages the other tumbler, whereby said tumbler and arm are movable simultaneously, and another tooth also carried by the arm and coacting with the tooth of the 5 first-mentioned tumbler.

9. In a lock, the combination with coacting rotatable tumblers, one of which is provided with a tooth, the other having an arcuate opening therethrough and provided with a 10 plurality of sockets, of an independently-rotatable arm carrying a spring-pressed holding-stud that detachably engages in the sockets of the tumbler, whereby said tumbler and arm are movable simultaneously, and a tooth 15 also carried by the arm, said tooth projecting through the arcuate opening and coacting with the tooth of the first-mentioned tumbler.

10. In a lock, the combination with a casing, of a post located within the casing and attached to one wall thereof, a tumbler mounted upon the post, an operating-stem extending through the wall of the casing opposite the wall to which the post is secured, said stem being in line with the post, and a connection 25 between the tumbler and the stem.

11. In a lock, the combination with a casing, of a stationary post located within the casing and attached to one wall thereof, a rotatable tumbler journaled upon the post, a rotatable 30 operating-stem extending through the wall of the casing opposite the wall to which the post is secured, said stem being in line with and bearing against the end of the post, and an arm secured to the stem and detachably connected to the tumbler.

12. In a lock, the combination with a casing, of a stationary post located within the casing, a tumbler rotatably mounted on the post and having a plurality of sockets, an operating- 35

stem projecting through the casing in line 40 with the post and having its inner end bearing against the outer end of said post, and an arm carried by the inner end of the stem, said arm being provided with a spring-pressed holding-stud that detachably engages in the sockets 45 of the tumbler.

13. In a lock, the combination with a casing having an open portion, of a movable closure for said open portion, a shackle pivoted to the casing, a latch for the shackle arranged within 50 the casing, tumblers located within the casing and having notches in their peripheries, a link pivoted to the latch and movable into the notches when they are in alignment therewith, and a spring interposed between and bearing 55 against the movable closure and the latch to urge the link into the notches.

14. In a lock, the combination with a casing having an open portion, of a closure for the open portion pivoted to the casing, a shackle 60 pivoted upon the casing, a latch for the shackle pivoted within the casing, a plurality of rotatable tumblers located within the casing and having notches in their peripheries, a link pivoted to the latch and having a hook that 65 is movable into the notches when they are in alignment therewith, said link having an integral spring cut therefrom and bearing against the pivoted closure to urge the hook of the link into the notches.

In testimony that I claim the foregoing as my own I have hereto affixed my signature in the presence of two witnesses.
